UNITED STATES PATENT OFFICE.

ISAAC W. GILES, OF NEW BEDFORD, AND CHARLES W. TOBEY, OF FAIRHAVEN, MASSACHUSETTS, ASSIGNORS TO ATLAS TACK COMPANY, OF FAIRHAVEN, MASSACHUSETTS, A CORPORATION OF MASSACHUSETTS.

MACHINE FOR VARNISHING EYELETS.

No. 858,339.

Specification of Letters Patent.

Patented June 25, 1907.

Application filed October 8, 1906. Serial No. 337,938.

To all whom it may concern:

Be it known that we, ISAAC W. GILES, a resident of New Bedford, and CHARLES W. TOBEY, a resident of Fairhaven, in the county of Bristol and State of Massachusetts, have invented an Improvement in Machines for Varnishing Eyelets, of which the following is a specification.

Japan or varnish has been applied to eyelets by hand and also by automatic means, and the eyelets have been then immediately subjected to the action of revolving cylindrical brushes for the purpose of spreading the varnish over the bell or flared portion of the eyelets. Such brushes do not, however, distribute the varnish with the desired uniformity, since the bristles project into the bell and do not act effectively on the rim of the same. We have found that a flat brush arranged to revolve in a plane parallel to the face of the eyelets is entirely effective and satisfactory for this purpose.

In carrying out our invention we employ two flat annular brushes which are arranged to revolve in opposite directions, whereby the varnish is distributed more evenly than would be practicable with a single brush. We have further devised improvements in the machine as will be hereinafter described and specifically indicated.

In the accompanying drawings—Figure 1 is a side view of our improved machine; Fig. 2 is a plan view of the same; Fig. 3 is an end view, some portions of the base being omitted; Fig. 4 is an enlarged vertical cross-section on the line 4—4 of Fig. 2; and Fig. 5 is an enlarged longitudinal section on the line 5—5 of Fig. 2.

A indicates parallel side bars of a rigid horizontal frame, which, in practice, is provided with suitable supports resting upon a horizontal foundation. These bars A are provided on the inner side, adjacent to the lower edge, with ledges a—see Figs. 2 and 4—upon which the cards x, containing the eyelets are supported while being carried or fed through the machine the bars A serve as side guides for the cards X while passing through the machine. Japan or varnish is applied to the faces of the eyelets, as indicated in Fig. 1, by means of rolls B, and the cards are advanced or fed by means of disks C, C', which are arranged in pairs one over the other, the

lower ones projecting upward through a space provided in the ledges a. It will be understood that the eyelet cards x, pass between these feed disks, which revolve in opposite directions. There are three sets of such feed disks, one being located near each end of the frame A, and one intermediately.

Rotation is imparted in the proper direction by means of intermediate friction gears D, these being arranged in a horizontal plane between the upper disks of the several sets. It will be understood that the lower disks C' of the several sets are rotated by frictional contact with the upper ones C. Motion is derived from any suitable power shaft, in this instance from the shaft E.

As indicated in Figs. 2 and 3, the upper feed disks C are mounted upon transverse shafts C', which are suitably journaled in the frame bars A, but the intermediate friction gears or disks D are arranged on one side only of the frame. A horizontal annular brush F is arranged under the frame A intermediate the lower disks C' of the first two sets of feed disks, and another similar brush F' is arranged correspondingly in the next space between the lower feed disks. As indicated by arrows, these brushes are rotated in opposite directions. I propose to employ any suitable means for rotating them, but, as indicated in the drawings, each of the brushes F, F', is provided with a vertical shaft G, which is connected by bevel gears H with horizontal shafts I, and the latter are in turn rotated by a belt and pulley by which they are operatively connected with the driving shaft E.

As the cards x holding the eyelets advance into the machine, as indicated in Fig. 1, they pass in contact with the upper one of the series of rolls B, and take up varnish therefrom. The edges of the card, which project laterally beyond the eyelets, slide on the ledges a and pass between the feed disks C, C', and thus forward and over the space in which the first brush F is arranged. The bristles of the latter work in contact with the varnished faces of the eyelets and distribute the varnish equally or uniformly, not only in the throat, but also over the rim of the same. In order to hold the cards against the upward pressure of the brush upon the eyelets, we arrange a horizontal guard plate J between the

frame bars A—see Figs. 1, 4, 5—and the upper or tubular ends of the eyelets slide in contact therewith. In order to perfect the distribution of the varnish, or in other words, to 5 secure its uniform dissemination over the bell and rim of the eyelets, they pass in contact with the second brush F', which, as before indicated, revolves in a direction opposite that of the first brush F. Besides this it will be 10 noted—see Fig. 2—that the brush F projects on one side of the frame and the brush F' on the other side of the same, one-half of each brush lying in the path of the eyelets as they travel through the machine. By this means 15 and by the annular form of the brush, they may be made of such size as to work more effectively on the eyelets.

What we claim is—

1. A machine for varnishing eyelets, comprising a frame having horizontal supports and side guides for cards holding eyelets, feed 20 disks for advancing the eyelet cards, said disks being spaced apart and arranged close alongside the side guides so as to bear on the edges of the cards outside the eyelets themselves, means for rotating said disks, flat 25 brushes arranged in a horizontal plane in the

path of the eyelets, means for revolving such brushes horizontally, and guards arranged over the brushes for resisting upward movement of the eyelet cards while being brushed, 30 substantially as described.

2. In a machine for the purpose specified, the combination, with a frame having guides for eyelet cards and means for feeding the 35 same therethrough, of two horizontal flat brushes arranged in the path of the eyelets, and means for revolving them in opposite directions horizontally, substantially as described. 40

3. In a machine for the purpose specified, the combination with a frame having supports and guides for eyelet cards and means for feeding the same therethrough, of a flat horizontal brush having an annular form and 45 arranged in the path of the eyelets, and means for imparting rotation thereto in a horizontal plane, substantially as described.

ISAAC W. GILES.
CHARLES W. TOBEY.
